DESIGN FOR A SUSPENDER

Hyman Schiller, New York, N. Y.

Application December 23, 1935, Serial No. 60,241

Term of patent 3½ years

To all whom it may concern:

Be it known that I, Hyman Schiller, a citizen of the United States, residing at New York city, in the county of New York and State of New York, have invented a new, original, and ornamental Design for Suspenders, of which the following is a specification, reference being had to the accompanying drawing, forming a part thereof.

Fig. 1 is a front elevational view of a suspender, showing my new design.

Fig. 2 is a rear elevational view of the same.

Fig. 3 is an outside face view of the same, portions of the strap elements have been broken away for convenience of illustration.

Fig. 4 is an enlarged fragmentary perspective view of Fig. 2 showing the portion in the dot and dash area.

Fig. 5 is a similar view showing the portion in the dot and dash area of Fig. 1.

I claim:

The ornamental design for a suspender, as shown.

In testimony whereof I have affixed my signature.

HYMAN SCHILLER.
